COMPOSITE BUILDING DECK

Michael G. Vass, Maywood, Ill., assignor to
United States Gypsum Company, Chicago, Ill.,
a corporation of Illinois

Application October 31, 1932, Serial No. 640,470

5 Claims. (Cl. 189—34)

This invention relates to building constructions, and has reference more particularly to metal decks for roofs or floors, together with locking means for connecting the adjoining decks, 5 one to the other, at points intermediate the supporting beams.

In the construction of metal decks for floors and roofs, it is customary to use elongated metal plates having depending flanges which rest upon 10 supporting beams or purlins. Where the depending flanges contact with the supporting beams or purlins, it is customary to provide clips which 15 securely attach the depending deck flanges to the flanges of the supporting beams or purlins. In view of the fact that the beams are usually spaced 20 comparatively far apart, it is desirable that the adjoining decks be securely attached together at points intermediate the supporting beams.

An object of this invention, therefore, is to 25 provide a building deck construction having means for locking the adjoining decks together at points intermediate of the supporting beams; also to improve building constructions in other respects hereinafter specified and claimed.

Reference is to be had to the accompanying 30 drawings forming a part of this specification, in which

Fig. 1 is a perspective view of one of my improved roof decks.

Fig. 2 is a perspective, sectional elevation 35 through a building deck construction.

Fig. 3 is a perspective view of one of the locking keys,

Fig. 4 is a sectional elevation through a pair of 40 adjoining metal decks showing the locking key in place,

Fig. 5 is a sectional elevation similar to Fig. 4, but showing a modified form of locking key,

Fig. 6 is a sectional elevation showing the form 45 of clip for attaching the decks to supporting beams,

Fig. 7 is a sectional elevation through a building deck construction at a point where the ends 50 of the decks overlap, and

Fig. 8 is a perspective view of one end of a modified form of deck construction.

One form of my improved metal deck shown in Fig. 1, consists of an elongated plate 10, having longitudinal channel shaped ribs 11 which divide 55 the plate 10 into two or more sections, as desired. At one end of the deck, the sides of the ribs 11 are substantially vertical, but at the nearest end of the deck, as seen in Fig. 1, the sides of the ribs 11 are caused to taper outwardly at a slight 60 angle by means of a gathering rib or bead 12

which extends from one end of the deck to a point somewhat less than the opposite end of the deck. The bead 12 also serves to reinforce the plate 10 in a longitudinal direction and makes said plates more resistant to loads which might 5 be placed upon them.

One longitudinal edge of the plate 10 is provided with a downwardly extending channel flange 13, which terminates at its lower edge in an arcuate shaped bulb channel 14 which has an 10 outwardly flaring lip 15 at the upper edge of said bulb channel. A downwardly extending flange 16 is formed along the opposite edge of each plate 10, the flange 16 terminating in an arcuate 15 shaped section 17 adapted to enter into and engage the inside of the bulb channel 14. The bulb channel 14 and section 17 thus form registering locking shoulders.

Due to the narrowing action of the reinforcing bead 12, the decks may be telescoped together 20 so that upon their erection on a sloping surface of a roof, they form a water shed immediately upon erection. Supporting beams or purlins 19 are positioned below the decks 10 preferably at the points where the ends of the decks telescope 25 together. The beams 19 preferably have outstanding upper flanges 20 which engage directly with the bottoms of the bulb channels. In order to securely attach the decks to the purlin flanges 20, a clip 22 is provided on top of the flange 20, 30 said clip having bifurcated ends 23, which are arranged to be bent around the flange 20. An upstanding flange 24 is formed on the clip 22 and is bent back upon itself to form a downstanding channel flange 25, which terminates in an arcuate section 26, said arcuate section being arranged 35 to fit within the bulb channel 14 of the adjacent building deck.

In order to securely lock adjoining building 40 decks together at one or more points intermediate the supporting purlins 19, I provide a locking key 28, which is composed of a flat strip of metal 29, formed into a cylinder 30 at its lower end, and having an upstanding flange 31 in closely abutting 45 relation to the metal strip 29. The tops of the strip 29 and the flange 31 are preferably in the same plane to form a shoulder 32 which may be used for hammering the locking key into position between deck flanges 13 and 16, so as to 50 press the arcuate flange section 17 tightly into locking position against the inner walls of the bulb channel 14 and section 17. It will be noted that the channel flange 14 extends through approximately 270 degrees so as to leave a substantially open throat to permit the transverse inser-

tion of the locking member 30. The metal forming the locking key 28 yields slightly and the metal deck flanges yield also when the locking key is being driven into locking position from 5 above the building deck.

A prong 33 is preferably formed integral with the metal strip 29 and extends upwardly to a point substantially above the deck plate 10. In constructing a roof, it is customary to mop asphalt on the top of the metal plate 10 and then apply a layer of insulating fiber board 35 to the asphalted surface. In applying the boards 35, the prongs 33 are forced through the boards until the board lies flush with the upper surface of 10 the plate 10, and then the board is locked in place by bending the prongs 33 at right angles to form locking flanges 36. A stiffening bead 34 is preferably formed in the middle of the prong 33 to 15 prevent the prong from bending over while it is being forced through the fiber board. Building paper 31, shingles, or other protective layers may be then applied on the fiber boards 35 by mopping on with asphalt or by other suitable means so as to make a water-shedding, heat insulating 20 roof construction. In constructing a floor, a short piece of round solid rod 39 may be used as a locking key; and then a slab of concrete, gypsum or other cementitious materials may be poured on top of the metal deck to form a floor. 25 Keys similar to keys 28, but without the prongs 33, may also be used.

If desired, a plate 42 may be made in long lengths of 20 or 30 feet and made in comparatively narrow widths, such as 6 to 12 inches (Fig. 35 8). In sections of this nature, it will be unnecessary to use intermediate beads 12 although it may be found desirable in certain cases. Flanges 13 and 16 are formed on the edges of the plate 42 in the same way that they are used on plate 10, 40 said flanges having the same shape as those shown on plate 10.

I would state in conclusion that while the illustrated examples constitute practical embodiments of my invention, I do not wish to limit myself 45 precisely to these details, since manifestly, the same may be considerably varied without departing from the spirit of the invention as defined in the appended claims.

Having thus described my invention, I claim 50 as new and desire to secure by Letters Patent:—

1. In a metal deck, a plurality of plates having overlapped ends, each plate having an outstanding flange extending longitudinally along one edge thereof, a channel flange extending longitudinally along the opposite edge of each plate 55 and adapted to receive the outstanding flange of

an adjoining plate, and a locking member driven into position within said channel flange in a direction perpendicular to the plane of said plates for locking adjoining plates together, said channel flange having a sufficient throat opening to permit the perpendicular insertion of said locking member. 5

2. In a metal deck, a plurality of plates arranged in a plane, each plate having an outstanding flange extending longitudinally along one 10 edge thereof, an open channel flange of substantially open throat extending longitudinally along the opposite edge of each plate and adapted to receive the outstanding flange of an adjoining plate, and a locking key driven into position in 15 a direction perpendicular to the plane of said plates and engaging said flanges for locking adjoining plates together.

3. In a metal deck, a plurality of plates arranged in a plane, each plate having an arcuate 20 outstanding flange extending longitudinally along one edge thereof, an arcuate channel flange of approximately 270 degrees extending longitudinally along the opposite edge of each plate, the arcuate section of the outstanding flange being 25 received in the arcuate channel flange, and a locking member forced into said channel flange from the face of said plates and engaging said outstanding flange so as to lock adjoining plates together. 30

4. In a metal deck, a plurality of elongated plates arranged in a plane, a channel flange formed along one longitudinal edge of a plate, said channel having a locking shoulder extending into said channel and a substantially open throat, 35 a longitudinal flange formed on the opposite edge of a plate, said longitudinal flange having an outstanding shoulder engaging the shoulder on the channel flange, and a locking rod forced transversely of the plane of said plates into said channel flange so as to secure said locking shoulders in locking position. 40

5. In a metal deck, a plurality of elongated plates arranged in a plane, a channel flange formed along one longitudinal edge of a plate, 45 said channel having a reentrant locking shoulder and a substantially open throat, a longitudinal flange formed on the opposite edge of said plate, said longitudinal flange being provided with an outstanding locking shoulder for engaging the locking shoulder of the channel flange, and key 50 means transversely driven in a direction perpendicular to the plane of said plate for securing said locking shoulders in locking relation. 55

MICHAEL G. VASS.
